(57) **CLAIM**

The ornamental design for a winch jack attachment bracket,
as shown and described.

DESCRIPTION

FIG. 1 is a perspective view of the winch jack attachment bracket of the present invention.

FIG. 2 is a top plan view.

FIG. 3 is a bottom plan view.

FIG. 4 is a front elevation. The rear elevation is identical to
the front elevation.

FIG. 5 is a side elevation taken from the right side of FIG.
4. The side elevation taken from the left side of FIG. 4 is
identical to FIG. 5; and,

FIG. 6 is a perspective view showing environment of the
present invention.

The broken line showing of a chain and hardware in FIG. 6
is for illustrative purposes only and forms no part of the
claimed design.
